United States Patent Office.

JOHN H. GARNHART, OF ST. LOUIS, MISSOURI.

Design No. 3,926, dated March 22, 1870.

DESIGN FOR BOTTLE.

The Schedule referred to in these Letters Patent and making part of the same.

To all whom it may concern:

Be it known that I, JOHN H. GARNHART, of the city and county of St. Louis and State of Missouri, have invented and produced a new and original Design for a Bottle, of which the following is a full, clear, and exact description, reference being had to the annexed photograph of same.

My invention consists in forming a bottle in the shape of a log cabin, and having its sides corrugated, so as to represent the logs of which it is constructed,

and also representing the doors and windows of same, as seen.

The illustration shows only two sides of the bottle, but the other sides are counterparts of these.

What I claim as my invention, and desire to secure by Letters Patent, is—

The design for a bottle, as shown.
